UNITED STATES PATENT OFFICE.

HARVEY W. SEIBER, OF DOVER, OHIO.

PLIER WRENCH.

Application filed September 8, 1924. Serial No. 735,645.

To all whom it may concern:

Be it known that I, HARVEY W. SEIBER, a citizen of the United States, residing at Dover, in the county of Tuscarawas and State of Ohio, have invented a new and useful Plier Wrench, of which the following is a specification.

This invention aims to provide novel means for operating the dog in a wrench 10 of the pliers type.

In the accompanying drawings:—

Figure 1 represents a side elevation of a wrench constructed in accordance with this invention;

Fig. 2 is a similar view of the under jaw 15 of the wrench;

Fig. 3 is an edge view of the wrench; and

Fig. 4 is a transverse section taken on the line 4—4 of Fig. 1.

The wrench claimed comprises a first lever 8 and a second lever 13, the levers having cooperating jaws 5 and 12. The second lever 13 has an elongated opening 11 disposed intermediate the ends of the second lever, and that lever has a rack 17 located along one edge of the opening 11, the first lever 8 having a circular aperture 3 located intermediate the ends of the first lever. A pivot element 21 connects the levers 13 and 8 and is located in the opening 11 of the second lever 13 and in the aperture 3 of the first lever 8. A dog 20 is disposed in the opening 11 of the second lever 13 and is mounted to swing on the pivot element 21, spring means 23 being provided for maintaining the dog yieldably engaged with the rack 17. The wrench embodies means whereby the first lever 8 will detach the dog 20 from the rack 17, when the levers 13 and 8 are swung apart to a predetermined angle. The wrench is characterized patentably by the fact that said means embodies an integral projection 22 on the dog 20, disposed radially with respect to the pivot element 21, the first lever 8 being supplied with an arcuate recess 4 communicating with the aper-

ture 3 of the first lever 8 and receiving the projection 22 of the dog for limited movement, the levers 8 and 13 being of single-layer form, and being superposed one on the other (meaning thereby that one lever does not fit within the other), the construction being such that the levers may be separated simply by removing the pivot element 21, and without loosening the projection 22 or separating it from the dog 20.

I claim:

A wrench comprising first and second levers having cooperating jaws, the second lever having an elongated opening disposed intermediate the ends of the second lever, and having a rack located along one edge of the opening, the first lever having a circular aperture located intermediate the ends of the first lever, a pivot element connecting the levers and located in the opening of the second lever and in the aperture of the first lever, a dog disposed in the opening of the second lever and mounted to swing on the pivot element, spring means for maintaining the dog yieldably engaged with the rack, and means whereby the first lever will detach the dog from the rack when the levers are swung apart to a predetermined angle, the wrench being characterized by the fact that said means embodies an integral projection on the dog, disposed radially with respect to the pivot element, the first lever being supplied with an arcuate recess communicating with the aperture of the first lever and receiving the projection of the dog for limited movement, the levers being of single-layer form, and being superposed one on the other, the construction being such that the levers may be separated simply by removing the pivot element, and without loosening the projection or separating the projection from the dog.

In testimony that I claim the foregoing as my own, I have hereto affixed my signature.

HARVEY W. SEIBER.
